US0D1002553S

(12) **United States Design Patent** (10) **Patent No.:** **US D1,002,553 S**
(45) **Date of Patent:** **** Oct. 24, 2023**

(54) **GASKET FOR CONNECTOR**

(71) Applicant: **Amphenol Corporation**, Wallingford, CT (US)

(72) Inventors: **Donald A. Girard, Jr.**, Bedford, NH (US); **Barbara Calderon**, Chelmsford, MA (US); **Marc B. Cartier, Jr.**, Durham, NH (US); **David Levine**, Amherst, NH (US); **David Manter**, Goffstown, NH (US)

(73) Assignee: **Amphenol Corporation**, Wallingford, CT (US)

(**) Term: **15 Years**

(21) Appl. No.: **29/814,128**

(22) Filed: **Nov. 3, 2021**

(51) **LOC (14) Cl.** **13-03**

(52) **U.S. Cl.**

USPC **D13/154**

(58) **Field of Classification Search**

USPC D13/153, 154, 184, 199; D23/269; D9/756, 760

CPC H01R 13/52; H01R 13/66; H01R 13/521; H01R 13/665

CLAIM

The ornamental design for a gasket for connector, as shown and described.

DESCRIPTION

FIG. 1 shows a front view of the gasket for connector;
FIG. 2 shows a rear view thereof;
FIG. 3 shows a left side view thereof;
FIG. 4 shows a right side view thereof;
FIG. 5 shows a top view thereof;
FIG. 6 shows a bottom view thereof;
FIG. 7 shows a top, front, left perspective view thereof;
FIG. 8 shows a bottom, front, right perspective view thereof;
FIG. 9 shows a top, rear, left perspective view thereof;
FIG. 10 shows a bottom, rear, right perspective view thereof;
FIG. 11 shows an enlarged cutaway view of a portion of the view shown in FIG. 7; and,
FIG. 12 shows an enlarged cutaway view of a portion of the view shown in FIG. 8.

The broken lines and adjacent surfaces show portions of the gasket for connector that form no part of the claimed design.

1 Claim, 10 Drawing Sheets
